CLAIM

The ornamental design for a combined clock, card holder, pen holder and paperweight, as shown and described.

DESCRIPTION

FIG. 1 is a front perspective elevational view of a combined clock, card holder, pen holder and paperweight, showing my new design;

FIG. 2 is a rear perspective view thereof;

FIG. 3 is a top plan view thereof;

FIG. 4 is a bottom perspective view thereof;

FIG. 5 is a side elevational view thereof; and,

FIG. 6 is a side, front elevational view thereof.

The broken lines shown in FIG. 1 are environmental only and form no part of the claimed design.
